WOOD TREATING TOOL

Raphael Rogers Poux, Orrville, Ohio

Application January 22, 1934, Serial No. 707,739

6 Claims. (Cl. 99—12)

This invention relates to wood-treating, and more particularly to a tool for impregnating with preservatives the walls of holes through wooden articles such as railroad ties.

5 Railroad ties, for example, are often impregnated with a wood-preservative solution, such as creosote, at a wood-treating plant before they are distributed for use. It is also a common thing to first bore holes in the ties for the reception of spikes, particularly screw spikes, the walls of these tie holes being impregnated with preservative when the ties are treated. However, if these holes are bored after the ties have left the wood-treating plant, or if additional 10 holes have to be bored to line up with holes in a different type of tie plate than anticipated, the walls of the tie holes are not protected by the preservative with which the remaining surfaces of the ties are impregnated, and are, therefore, 15 subject to decay. This is also true of other types of wooden articles, such as telephone poles and the like, when holes are bored in them after they have been impregnated with a wood-preservative solution.

20 It is an object of this invention to provide a tool for impregnating with preservatives the walls of holes through wooden articles, such as railroad ties. Further objects are to provide a tool of this kind which can be used efficiently with preservatives under high pressure, which is simple in construction and easy to operate, which is light in weight, and which is adapted to be quickly and easily put in operating position and removed therefrom. A still further object is to 25 provide a wood-treating tool which can be used with railroad ties to which rails are spiked, without removing the ties from their position on the roadbed.

In accordance with this invention, a nozzle is 30 provided for insertion in a hole through a wooden article. A pair of spaced sealing members is carried by the nozzle in such position as to be disposed in the opposite ends of the hole with whose wall they are forced into sealing engagement by means acting in cooperation with the nozzle. The nozzle is provided with a passage for connecting the space between the two sealing members to an outside source of wood-preservative solution by which the walls of the hole is 35 impregnated.

The preferred embodiment of the invention is illustrated in the accompanying drawing, of which Fig. 1 is a vertical section through the apparatus shown disposed in a hole bored through 40 a wooden railroad tie; and Fig. 2 is a fragmentary view, similar to Fig. 1, of the lower portion of the apparatus with the lower sealing member in sealing engagement with the wall of the tie hole.

In Fig. 1 of the drawing there is shown a fragmentary vertical section of a wooden railroad tie 1 on top of which rests a tie-contact member or head 2 having a vertical bore 3 therethrough axially aligned with a spike-receiving hole 4 bore through the tie.

45 Slidably disposed in bore 3 of head 2 is an elongate member 6, shown in the form of a rod whose inward or downward movement is limited by a shoulder 7, formed in bore 3, abutting against a shoulder 8 formed on the rod by enlarging its upper end portion. This enlarged portion also serves to strengthen the exposed portion of the rod which extends above the tie contact member. The opposite end of rod 6 extends through tie hole 4.

50 In order to permit a wood-preservative solution, such as creosote, to be forced into the wall of hole 4 under high pressure so as to thoroughly impregnate it, means are provided for sealing the ends of the hole to prevent escape of the preservative while it is being applied. These means include a pair of sealing members or gaskets 9 and 11 through which rod 6 slidably extends, and which are spaced apart preferably at such a distance as to be disposed in the opposite ends of 55 the tie hole. The sealing members are made of resilient material such as rubber, and conform to the cross-sectional configuration of the hole. Gasket 9, at the inner or lower end of the rod, is held thereon by a nut 12 and a washer 13. The outer face of gasket 11, at the opposite end of the tie hole, bears against the lower face of head 2.

55 As will be seen in Fig. 1, there is normally a slight clearance between the gaskets and the wall of tie hole 4 to enable this wood-treating apparatus to be readily inserted into or removed from tie holes without binding. Consequently, before the gaskets can seal the ends of hole 4 they must be expanded into sealing engagement with its wall. A convenient and simple way of accomplishing this is to compress the gaskets axially, whereupon they expand radially as shown in Fig. 2. To this end, means is provided for moving rod 6 outward relative to head 2 in order 60 to exert pressure on gasket 9 in the direction of gasket 11. However, as means also is provided for spacing the two gaskets a predetermined fixed distance apart, this pressure can act only to compress each gasket axially, whereby they are 65

expanded radially and forced into engagement with the tie.

To permit rod 6 to be moved outward relative to the tie contact member, a lever 14 is fulcrumed 5 on a pivot pin 16 which is journaled in a handle member 17 rigidly connected in any suitable manner to the tie contact member 2. The short arm of the lever is bifurcated to permit it to straddle rod 6 with forks 18 bearing against the 10 lower surface of an outwardly extending flange 19 formed on the upper end of the rod. Preferably, the upper faces of forks 18 are convex, so the contact area between them and flange 19 remains substantially uniform as lever 14 is raised 15 or lowered.

The two sealing gaskets are maintained a pre-determined fixed distance apart by a rigid spacing member, a tube 21 loosely telescoped on rod 6 being suitable for this purpose. Washers 22 20 are interposed between the ends of the tube and the inner faces of the sealing gaskets to distribute pressure evenly over those faces when gasket 9 is moved in the direction of gasket 11.

This wood-treating apparatus is placed in operating position by inserting the gasket-carrying portion of rod 6 and its associated parts into tie hole 4 until head 2 engages tie 1, whereupon sealing gaskets 9 and 11 are found to be disposed in the opposite ends of hole 4. Lever 14 is then 25 manually squeezed toward handle member 17 to raise rod 6 and force nut 12 and washer 13 against lower gasket 9. The tendency of this gasket to rise with the rod is restricted by tube 21, washers 22 and upper gasket 11, all interposed 30 between gasket 9 and head 2 which remains in contact with the tie. The result is that the pressure exerted through rod 6 acts to compress the yielding gaskets axially and expand them 35 radially until their sides are in tight contact with 40 the wall of the tie hole (Fig. 2).

The problem of introducing wood-preservative solution into the tie hole between its sealed ends is solved by providing the upper portion of rod 6 with an axial bore 23 extending from its outer 45 end to a point between the sealing gaskets. The inner end of this bore is opened into hole 4 by means of an intersecting radial bore 24. A source of wood-preservative under pressure is connected 50 with axial bore 23 by a flexible conduit 26 suitably joined to the outer end of the rod, the flow of 55 preservative being controlled by a valve (not shown) in the conduit.

When the valve is opened, wood-preservative is forced through rod bores 23 and 24 and into 55 the tie hole, tube 21 being provided at intervals with openings 27 through which the preservative passes to the wall of hole 4 where impregnation occurs, telescopically-disposed rod 6 and tube 21 functioning as a nozzle for the introduction of 60 the preservative. When the treatment is over, the valve is closed and lever 14 is released, which allows the resilient gaskets to resume their normal shapes and to be easily withdrawn from the tie.

65 It will be apparent that the wood-preserving solution is confined by the sealing gaskets to the wall of the tie hole, and that the seals are sufficiently strong to permit the required amount of pressure to be applied to the preservative. As 70 both of the gaskets are carried by the same member and are inserted in the tie hole rather than attached over its ends, they are both applied from the same side of the tie. Consequently, the tie does not have to be laid on its side or turned 75 over to seal the lower end of the hole. A further

advantage of this structure is that it is unitary, thereby eliminating the trouble of caring for and applying several loose parts.

According to the provisions of the patent statutes, I have explained the principle and mode 80 of operation of my invention, and have illustrated and described what I now consider to represent its best embodiment. However, I desire to have it understood that, within the scope of the appended claims, the invention may be practiced 85 otherwise than as specifically illustrated and described.

I claim:

1. A tool for impregnating walls of holes 90 through wooden articles with preservative solutions, comprising an elongate member for insertion in a hole, a pair of spaced sealing members carried by said elongate member, and means cooperating with said elongate member for forcing the sealing members into sealing engagement 95 with the wall of the hole, said elongate member being provided with a passage for the flow of preservative solution to the space between the sealing members.

2. A tool for use in impregnating walls of holes 100 through wooden articles with preservative solutions, comprising an elongate member for insertion in a hole, a pair of spaced sealing members carried by said elongate member, and means cooperating with said elongate member for forcing 105 the sealing members radially outward into sealing engagement with the wall of the hole, said elongate member being provided with a passage for the flow of preservative solution to the space between the sealing members. 110

3. A tool for use in impregnating walls of holes 115 through wooden articles with preservative solutions, comprising an elongate member for insertion in a hole, a pair of spaced yielding gaskets carried by said elongate member and so positioned as to be disposed in the opposite ends of said hole, and means cooperating with said elongate member for compressing the sealing members axially to force them radially outward into sealing engagement with the wall of the hole, said 120 elongate member being provided with a passage for connecting said hole between the sealing members to a source of high pressure preservative outside of said hole.

4. A tool for impregnating with a preservative 125 solution the walls of holes through wooden articles such as railway ties, comprising a head, a nozzle insertable in a hole and including a pair of telescopically-disposed members, a pair of laterally expandable gaskets carried by said nozzle 130 adjacent to its ends, and means on said head for moving said members axially with relation to each other to expand said gaskets into sealing engagement with the wall of a hole, the tool being provided with a passage for the flow of a preserv- 135 ative solution to the space between the gaskets.

5. A tool for impregnating with a preservative solution the walls of holes through wooden articles such as railway ties, comprising a head provided with an opening therethrough, a nozzle insertable in a hole and including a pair of telescopically-disposed members the inner of which projects through the opening in said head, a pair of laterally expandable gaskets carried by said inner telescoping member at each end of the 145 outer of said members, and means on said head for moving said inner member axially relative to said outer member to expand said gaskets into sealing engagement with the wall of the hole, the tool being provided with a passage for the flow of 150

a preservative solution to the space between the gaskets.

6. A tool for use in impregnating walls of holes through wooden articles with preservative solutions, comprising an elongate member for insertion in a hole, a pair of spaced resilient gaskets carried by said elongate member and so positioned as to be disposed in the opposite ends of said hole, means mounted on the inner end of said elongate member for bearing against the outer face of the adjoining gasket, means disposed at the opposite end of the hole in fixed posi-

tion relative thereto and bearing against the adjoining gaskets, rigid means spacing the gaskets apart and movable longitudinally relative to the elongate member, and means for moving said elongate member outwardly whereby said gaskets are compressed axially and forced radially outward into sealing engagement with the wall of the hole, said elongated member being provided with a passage for connecting said hole between the sealing members to a source of high pressure preservative outside of the hole.
